UNITED STATES PATENT OFFICE

ADOLPH T. JOHANSON, OF CHICAGO, ILLINOIS

WATER HEATER

Application filed January 13, 1930. Serial No. 420,350.

My invention pertains to water-heaters and relates more particularly to structures of this character which may be inserted in or removed from the heating apparatus of a furnace, thus facilitating the original installation of such part of the appliance and rendering its removal or withdrawal, when occasion requires, a matter of easy and rapid accomplishment.

10 To enable those trained and skilled in this art to have a full and complete comprehension of the invention, both from structural and performance standpoints, in the accompanying drawings, forming a part of this specification, I have illustrated a present, preferred embodiment of the invention as applied to an incinerator and, for simplicity, the same parts of the apparatus, throughout the several views, have been 20 designated by like reference numerals.

In these drawings:

Figure 1 is a vertical section through the heating apparatus and illustrates several of the water-heating units in place;

25 Figure 2 is a vertical section through one of the units on an enlarged scale on line 2—2 of Figure 4;

Figure 3 is a fragmentary front elevation of the pipe connections to the units;

30 Figure 4 is a vertical section on line 4—4 of Figure 2; and

Figure 5 is a similar section on line 5—5 of Figure 2.

Referring to the drawings, it will be noted 35 that the hot combustion gases of the incinerator, characterized as a whole 11, pass upwardly through the chamber 12 to the flue 13 and that such chamber is traversed by any appropriate number of the 40 water-heating units, each designated as a whole as 14.

Each such unit comprises a round head connector 15 having a larger portion 16 and an adjacent part 17 of slightly less diameter.

The smaller section 17 of each such member 15 fits in a round hole of corresponding size in a metal plate 19 positioned against the outer surface of one of the brick or refractory walls 21 defining the internal cham-

ber or compartment 12, such plate constituting the inner wall of a sheet-metal cabinet having the top, bottom and side walls 22, 23, 24 and a door 25 which may be opened when occasion requires.

55 Such head connector is internally divided into upper, intermediate and lower chambers 26, 27, 28, respectively, by curved, division walls or partitions 29 and 31.

The lower chamber 28, by means of an 60 elbow 32 and a union 33, is connected to a cold-water admission-pipe 34 common to all of the connectors 15 located at the same level, and, in comparable manner, the upper chamber 26 is joined by an elbow 35 and a union 65 36 to a hot-water discharge-pipe 37 similarly connected to all the other connectors of the same horizontal row.

Chamber 28 is connected by a water-heating tube 38 to a chamber 39 of a round or 70 cylindrical rear connector 41 of the same external diameter as that of the reduced part 17 of the companion connector 15, such member 41 occupying a correspondingly-shaped hole 42 of substantially the same size in a 75 metal plate 43 located outside of and against the opposite brick or refractory wall 44 of the chamber 12, the plate 43 forming part of a sheet-metal cabinet 45 having a door 46.

Connector 41 is divided into two chambers 80 39 and 47 by an inclined wall 48 as shown in Figure 5.

Chamber 39 of such rear connector is joined to chamber 27 of the head connector 15 by a tube 49, and such latter chamber in 85 turn is united to chamber 47 of the rear connector by a suitable tube 51.

Also, chamber 47 is in communication with chamber 26 through a tube or pipe 52.

The water traversing the system flows 90 through the several connected elements in the following order—34, 33, 32, 28, 38, 39, 49, 27, 51, 47, 52, 26, 35, 36, 37.

In making this passage the water flows through the four tubes or pipes in series relation and is consequently subjected four times to the hot products of combustion passing upwardly about the pipes.

The two end connectors and the intervening tubes or pipes constitute a single unitary

structure and this may be installed in the heater by sliding it into place through the aperture 18 until the annular shoulder of the member 15 strikes the plate 19 which 5 assures that the unit has been pushed fully home and is in correct position.

As is clearly illustrated, the brick walls 21 and 44 are apertured at 53 and 54, respectively, to receive portions of the heater 10 unit and after the latter is in place such holes are filled with asbestos packing, fire clay, or any other suitable material 55.

If, for any reason, it is desired to remove 15 or demount any such heating unit, as for repairs, or substitution of another heater, or to reduce the water-heating capacity of the structure, the unions 33 and 36 are unscrewed and the elbows 32 and 35 removed.

Then the whole unit is pulled out forwardly 20 through the aperture or opening 18, the packing 55 breaking away as may be required to allow such removal.

The connector 41, during such withdrawal 25 of the unit, can readily pass through the opening 18 because it is no larger in diameter than the latter.

When the unit is in place, its two ends are supported in very large measure, if not 30 entirely, by the two metal plates 19 and 43 on the margins of whose openings it rests and by which it is borne.

Both end connectors of each unit are provided with screw-threaded holes fitted with 35 plugs 56, 58 in register with the plurality of tubes or pipes which afford access thereto for cleaning purposes.

Obviously, as few or as many of the heating 40 units may be employed as the particular installation demands and the number used may at any time be changed to meet modified conditions.

Those acquainted with this art will readily understand that the invention, as defined 45 by the appended claims, is not limited and restricted to the precise and exact details of structure illustrated and described and that the appliance may be modified within radical degree without departure from the heart and essence of the invention and without the sacrifice of any of its material and substantial benefits and advantages.

I claim:

1. In a heater having a passage for hot 50 combustion gases with opposite walls apertured in register, the combination of a metal-plate on the outer face of one of such walls and having an aperture therethrough in register with the corresponding wall aperture, a second metal-plate on the outer face of 55 the other wall apertured in register with its aperture, a water-heating unit consisting of a connector mounted in the aperture of and supported in substantial measure by said second plate, a second connector mounted in 60 the aperture of and supported in material

measure by said first plate, said second connector having an external shoulder adapted to engage the outer face of the correlated plate, a plurality of tubes uniting said connectors, means to admit water into and to 70 permit its discharge from one of said connectors, and packing in and filling the otherwise unoccupied space of said wall apertures, said unit being capable of withdrawal as a unitary structure through said second 75 plate aperture.

2. In a heater having a passage for hot 80 combustion gases with opposite walls apertured in register, the combination of a metal-plate on the outer face of one of such walls and having an aperture therethrough in register with the corresponding wall aperture, a second metal-plate on the outer face of the other wall and apertured in register with its aperture, a water-heating unit consisting of a connector mounted in the aperture of and supported in substantial measure by said second plate, a second connector mounted in the aperture of and supported in material measure by said first plate, 85 a plurality of tubes uniting said connectors, means to admit water into and to permit its discharge from one of said connectors, and packing in and filling the otherwise unoccupied space of said wall apertures, said unit 90 being capable of withdrawal as a unitary structure through said second plate aperture.

3. In a heater having a passage for hot 95 combustion gases between opposite walls with a registering cavity and aperture there- 100 in respectively, a water-heating unit consisting of a hollow connector divided into chambers by partition means in the cavity of one of said walls, a second hollow connector divided into chambers by partition 105 means in the aperture through the opposite wall, tubes crossing said passage and joining said connector chambers together, whereby a liquid may flow through such tubes in 110 series, means to admit water to be heated to said unit, and means to deliver the heated water from said unit, said aperture being of a size to permit withdrawal of said unit therethrough as a unitary structure. 115

In witness whereof I have hereunto set my hand.

ADOLPH T. JOHANSON.
